US00D821546S

(12) **United States Design Patent** (10) **Patent No.:** **US D821,546 S**
Fletcher et al. (45) **Date of Patent:** **** Jun. 26, 2018**

(54) **ACTUATED VALVE**

(71) Applicants: **David E. Fletcher**, Flint, MI (US); **Brian M. Graichen**, Leonard, MI (US); **James H. Miller**, Ortonville, MI (US); **Rex Bravo**, Detroit, MI (US); **Keith Hampton**, Ann Arbor, MI (US); **Matthew C. Gilmer**, Whitmore Lake, MI (US); **Andrew D. Niedert**, New Hudson, MI (US); **Nicole Bruder**, Harrison Township, MI (US)

(72) Inventors: **David E. Fletcher**, Flint, MI (US); **Brian M. Graichen**, Leonard, MI (US); **James H. Miller**, Ortonville, MI (US); **Rex Bravo**, Detroit, MI (US); **Keith Hampton**, Ann Arbor, MI (US); **Matthew C. Gilmer**, Whitmore Lake, MI (US); **Andrew D. Niedert**, New Hudson, MI (US); **Nicole Bruder**, Harrison Township, MI (US)

(73) Assignee: **DAYCO IP HOLDINGS, LLC**, Troy, MI (US)

(**) Term: **15 Years**

(21) Appl. No.: **29/622,740**

(22) Filed: **Oct. 19, 2017**

(57) **CLAIM**

The ornamental design for an actuated valve, as shown and described.

DESCRIPTION

FIG. 1 is a front perspective view for an actuated valve showing our new design;

FIG. 2 is a front elevation view of the actuated valve thereof; FIG. 3 is a rear elevation view of the actuated valve thereof; FIG. 4 is a left-side elevation view of the actuated valve thereof;

FIG. 5 is a right-side elevation view of the actuated valve thereof;

FIG. 6 is a top view of the actuated valve thereof; and,

FIG. 7 is a bottom view of the actuated valve thereof.

The broken lines shown in the figures are included for the purpose of illustrating portions of the actuated valve and form no part of the claimed design.

1 Claim, 4 Drawing Sheets
